UNITED STATES PATENT OFFICE.

ARTHUR J. WILLS, OF BROOKFIELD, MASSACHUSETTS; MABEL BARTON WILLS
EXECUTRIX OF SAID ARTHUR J. WILLS, DECEASED.

MACHINE FOR PLAITING FABRIC, PARTICULARLY RUBBER FABRIC.

1,281,463.

Specification of Letters Patent.

Patented Oct. 15, 1918.

Application filed May 31, 1916. Serial No. 100,837.

To all whom it may concern:

Be it known that I, ARTHUR J. WILLS, of Brookfield, in the county of Worcester and State of Massachusetts, a citizen of the 5 United States, have invented a new and useful Improvement in Machines for Plaiting Fabric, Particularly Rubber Fabric, of which the following is a specification.

In the manufacture of rubber bathing 10 caps, other rubber apparel and the like demand has come for trimming which shall be plaited, and heretofore this demand has been supplied by hand-made material.

My invention relates to a machine especially adapted to plait a strip of rubber to make such trimming, the plaited material being tacked, that is, put under heavy pressure at the moment the plait is made so that the adhesive quality of the unvulcanized or 20 semi-vulcanized material may be utilized to keep the plaits in proper condition until such time as they are attached to the articles to be trimmed.

My invention will be understood by reference to the drawings in which it is shown in its preferred form, for I realize that features of it may be embodied in a variety 25 of ways.

Figure 1 is a front elevation of a machine 30 embodying my invention, the shaft being shown in section.

Fig. 2 is a plan thereof.

Fig. 3 is a side elevation taken from the left side of the machine as shown in Fig. 2.

35 Fig. 4 is a side elevation looking from the opposite side, the guideway being removed.

Fig. 5 is a longitudinal section of the shaft showing the arrangement of cams upon the shaft.

40 Figs. 6, 7 and 8 are cross sections taken on lines 6—6, 7—7 and 8—8 of Fig. 3.

Figs. 9, 10, 11 and 12 are details showing operations of the machine upon the fabric.

Fig. 13 is a plan view of the finished 45 fabric,

Fig. 14 being a cross section thereof.

A is a base on which is mounted a frame comprising two standards A¹, A² connected at the bottom by the piece A³ which rests 50 on the base A, the standards serving as bearings for the shaft B and providing guideways for certain of the parts as below described. One end of the shaft B carries a pulley C by which power is applied to 55 run the shaft. The other end carries a

hand-wheel C¹ attached to the shaft by a set screw c, this hand-wheel enabling the shaft to be moved when not under power. On the front end of the shaft is a sleeve C² which is made fast with one of the standards A¹ by means of the set screw c¹ and within which the shaft turns.

Mounted on the sleeve C² to turn thereon is the plaiting wheel D. This wheel comprises a disk from the face of which projects a series of pins d, each pin being preferably set into a suitable opening in one face of the plaiting wheel and held in place by a set screw d¹. In the rear of the plaiting wheel and attached thereto is a 65 ratchet E having a number of teeth corresponding with the number of pins d. The plaiting wheel D, while it is free to move about the sleeve C², is frictionally connected thereto as by a suitable strip D¹ of fiber 70 board or the like, which lies in a recess in the plaiting wheel and rests on the sleeve, bearing on the said strip, and extending radially to the periphery of the plaiting wheel is a screw d² whereby the frictional 75 contact between the strip D¹, which is part of the plaiting wheel D, and the sleeve C² may be adjusted, this construction being such that upon the rotation of the ratchet which is free to turn upon the shaft B, the 80 plaiting wheel will be rotated therewith, but will otherwise not be moved in the ordinary 85 movement of the machine.

The ratchet and plaiting wheel are given an intermittent movement by a pawl E¹, 90 which is hung from a rocking member F, f being the rod about which the rocking member rocks and by which one end of it is supported. The rod f is mounted at one end in a plate f¹ mounted on top of a bracket F¹ attached to the standard A¹. One end 95 of this rocking member F rests on and is lifted by a cam F² mounted on the cam shaft B on which it rests, f² being a spring, one end of which is connected to the member F, the other end being connected to a pin f³ 100 projecting from the standard A¹.

It will be seen that rotation of the shaft will cause the raising of the free end of the rocking member F and the pawl E¹, and a 105 consequent rotary movement of the ratchet E and plaiting wheel D, the cam, however, being of such shape that the plaiting wheel D will be moved only the distance of one pin d.

H is a presser foot mounted upon the member F so that it rocks therewith as will be below described.

Between the plaiting wheel D and the standard A¹ there is mounted to turn on the sleeve C² a presser table G, this table having a rocking motion which is given to it by means of a lever G², mounted on the horizontal portion A³ of the frame and fulcrumed at 10 g. It is connected at one end by the link G¹ to the presser table and at the other end to a slide G³. This slide runs in a suitable guideway in the standard A², being held in place by straps g¹, g² and being maintained 15 in its upper position by means of the spring g³ one end of which is attached to it, the other end being attached to the strap g². This slide is operated by a cam G⁴ of suitable shape and engaging a cam roll g⁴ mounted 20 on a pin connected to the slide G³ by an arm g⁵. The radius of the presser table at its front or working end, that is the end farthest from its connection with the link G¹, is nearly sufficient to reach the circle of pins 25 d upon the plaiting wheel D, the distance, however, between the presser table and the pins being about double the thickness of the material to be plaited, and this radius is maintained rearwardly from that point for 30 the distance of five or more pins, when it abruptly terminates at a shoulder g⁶ and from that point rearwardly the diameter of the presser table is less in order to facilitate the removal of the plaited fabric therefrom. 35 The plunger by which the material is looped between the pins d is shown at J and comprises a plate somewhat wider than the length of the pins d and sufficiently thin to carry the fabric down between two of the 40 pins. This plunger is mounted upon a frame comprising a horizontal member J¹ having a vertical arm J² which passes down between straps J³ supported upon the standard A². This vertical member J² carries a 45 cam roll j riding on a cam J⁴, this cam being mounted on the shaft B to rotate constantly therewith. A spring J¹, the lower end of which is attached to the frame A³ and its upper end to a projection from the arm J², 50 holds the cam roll against the cam.

The tacker comprises a member K attached to a downwardly-projecting end of the horizontal member K¹ of a slide K². This slide K² is supported in guideways formed by the 55 straps J³ and is held in its uppermost position by a spring k, one end of which is attached to the slide K² and the other to one of the straps J³. Movement is given to this tacker K by means of the cam roll k¹ attached to the slide K² and the cam K² mounted 60 on the shaft B.

The tacker is somewhat concaved at its lower surface to coöperate with the curve of the presser table. It is provided with teeth 65 so that it is adapted to engage the fabric be-

low it and apply pressure to the fabric, the fabric being supported by the pins and the presser table. It is well known that layers of thin sheet rubber if slightly vulcanized are capable of being stuck together under 70 pressure, and by means of the tacker, the presser table and the pins the product is fastened in plaited condition for further vulcanization or manufacture. The tacker K as shown is a thin plate of about the thickness of $\frac{1}{8}$ of an inch, though it may be somewhat thicker, and the material which has passed under it and been engaged by its lower edge has all the appearance of being 75 tacked.

L is a guide table located to feed the material to be plaited to the machine, and as shown it is provided with an adjustable wall L¹ slotted and attached to it by screws l so that the material may be properly fed to the 80 machine.

The operation of my machine is as follows:—

The machine being in the position shown in Fig. 1, the material M is fed in over the 90 guide table L under the presser foot H, and at the start the end is carried along by hand as shown in M¹ in Fig. 9 for a sufficient distance so that it may be held by the hand of the operator until the plaiting is sufficiently 95 well begun so that the machine has acquired a hold on the material. The first step is the downward thrust of the plunger which pushes a loop m of the material between two of the pins d, which serve as a work support, 100 thus carrying it within the circle of the pins on the plaiting wheel (see Fig. 10). The plunger gets its slack from the free end of the fabric M, which is drawn in over the guide table L, the other end of the fabric being held by the tacker, and when the plunger has reached the extreme of its movement the presser foot falls and binds the fabric against one of the said pins so that the plunger will not withdraw the fabric on 105 its upward movement. The presser foot is shown in its upper position in Fig. 9 when the plunger is beginning its down stroke, while in Fig. 10 the plunger has completed its stroke and the presser foot clamps the 110 material. The tacker K rises when the plunger is about to rise, while the presser table moves to the right and wipes the material in front of it (see Fig. 11), so that the plait thus made is thoroughly shaped. The presser table and plaiting wheel then move to the left and the presser foot rises simultaneously with the movement of the pawl, which gives the plaiting wheel its movement, to bring another space into register with the 115 plunger, when the tacker descends pressing the work between it and the presser table, and the operation is repeated. It will be seen that each plait is impressed by the tacker several times as the plaiting wheel 120

125 plunger, when the tacker descends pressing the work between it and the presser table, and the operation is repeated. It will be seen that each plait is impressed by the tacker several times as the plaiting wheel 130

moves around step by step so that it is quite firmly stuck in place by the natural cohesion of the fabric.

All that finished material which is to the 5 left (see Figs. 9-12) of the tacker is quite loosely held on the pins *d* and may be easily slipped off therefrom by the operator as may be desirable, so that the wheel *D* is never blocked with finished material. This 10 is due to the fact that the rear part of the presser table is of less diameter than the front thereof.

I have shown above the best form of my invention now known to me, but the various 15 elements may be differently operated to produce the desired result. It is evident, for example, that if the material to be plaited be something other than rubber other tacking means might be substituted for that shown, or 20 the edge of the material may be gummed and the material run through the machine in such a way that the plaited gummed edge will come under the stitcher. Other changes in the machine which will fall within the 25 scope of the claims will suggest themselves to those skilled in the art.

What I claim as my invention is:—

1. A machine of the kind described comprising a work support, means for giving it 30 an intermittent rotary movement, a looping mechanism, and a tacking mechanism.

2. A machine of the kind described comprising a work support, means for giving it an intermittent rotary movement, a looping 35 mechanism, clamping means operable in connection with said looping mechanism to hold the fabric against said work support, and a tacking mechanism.

3. A machine of the kind described, comprising a guide table, a work support, a looping mechanism, a presser table, a presser foot operable in connection with said looping mechanism to hold the fabric upon said 40 presser table, and a tacking mechanism.

4. A machine of the kind described, comprising a feeding mechanism, a work support comprising a plaiting mechanism having a plurality of pins extending horizontally outward from its external vertical 45 surface, a looping mechanism, and a tacking mechanism.

5. A machine of the kind described, comprising a work support comprising a plaiting wheel having a series of horizontal pins 55 extending outwardly near the periphery of its external vertical surface, means for imparting an intermittent movement to said wheel, a looping mechanism, and a tacking mechanism.

6. A machine of the kind described, comprising a plaiting wheel having a plurality of horizontal pins extending outwardly near the periphery of its external vertical face, a looping mechanism, a presser table adjac- 60 cent said wheel, means for moving said

wheel whereby said wheel will be moved but the distance of one pin at a time, and a tacking mechanism.

7. A machine of the kind described, comprising a guide table, a work support, means for imparting an intermittent movement thereto, a presser table located adjacent said work support and adapted to have a rocking movement and during said movement in one direction to press the work against said 75 work support, and move therewith, a looping mechanism, and a tacking mechanism.

8. A machine of the kind described, comprising a work support, means for imparting an intermittent rotary movement thereto, a presser table located adjacent said work support, means for imparting an oscillating movement to said presser table, said movement in one direction pressing the work held by the work support and in the opposite direction being with the work support and work, a looping mechanism, and a tacking mechanism.

9. A machine of the kind described, comprising a work support, means for imparting an intermittent rotary movement thereto, a presser table located adjacent said support, means for imparting an oscillating movement to said presser table, its movement in one direction taking place simultaneously 95 with the movement of said support and in the same direction therewith, a looping mechanism, clamping means to hold the fabric upon said presser table operable in connection with said looping mechanism, and a 100 tacking mechanism.

10. A machine of the kind described, comprising a feeding mechanism, a work support comprising a plaiting wheel having a series of pins extending horizontally outward near the periphery of its external vertical face, a presser table located adjacent said wheel and directly beneath said pin, means for imparting an intermittent movement to said wheel, means for imparting an 105 oscillating movement to said table, a looping mechanism, and a tacking mechanism, the radial distance between said table and said pins from the front rearward to a shoulder thereon being about double the thickness of 110 the fabric and the radial distance from the edge of said table to the axis of the table rearward from said shoulder being less than the radial distance of said table forward of 115 said shoulder.

11. A machine of the kind described, comprising a feeding mechanism, an intermittently rotating work support, a looping mechanism comprising a plunger located above said work support, means for imparting an intermittent movement to said plunger, and a tacking mechanism.

12. A machine of the kind described, comprising a work support, means for imparting an intermittent rotary movement thereto,

a looping mechanism comprising a plunger located above said work support, means for imparting an intermittent movement thereto while said work support is stationary, and 5 a tacking mechanism.

13. A machine of the kind described, comprising a feeding mechanism, a rotary work support, an oscillating presser table located adjacent thereto, a looping mechanism comprising a plunger located above said work support and above the forward end of said presser table when said presser table is in its rearward position, means for imparting movement to said plunger, and a tacking 10 mechanism.

14. A machine of the kind described, comprising a feeding mechanism, a rotary work support, an oscillating presser table adjacent thereto, a looping mechanism comprising a plunger located above said work support and said table and adapted on its downward stroke to loop the fabric upon the work support, means for imparting an intermittent movement thereto, clamping 20 means operable in connection with said looping means whereby when the plunger is withdrawn the fabric will be held upon the work support, and a tacking mechanism.

15. A machine of the kind described, comprising a work support comprising a plaiting wheel having a series of pins near the periphery of its external vertical face, means for moving said wheel a distance of one pin at a time, a presser table located adjacent said 30 wheel and beneath said pins, means for moving said table rearward simultaneously with the movement of said wheel, a looping mechanism comprising a plunger located above said wheel and above the forward end of said table and adapted on its downward stroke to loop the fabric about one of said pins, means for moving said plunger when the wheel is stationary, clamping means operable to hold the fabric about said pins as 35 said plunger is raised, and a tacking mechanism.

16. A machine of the kind described comprising a reciprocating tacker, a looping mechanism operable while the tacker is in 40 tacking position, means for holding the fabric during the withdrawal of the looping mechanism, and a reciprocating presser table adapted to engage the loop and press it and the fabric under the tacker.

55 17. A machine of the kind described, comprising a feeding mechanism, a work holder, a looping mechanism, a presser table lo-

cated adjacent said work holder, a tacking mechanism comprising a tacking member having a concave lower surface to coöperate with said presser table, said tacking member 60 also being provided with teeth to engage the fabric.

18. A machine of the kind described, comprising a work holder, means for imparting an intermittent movement thereto, a looping mechanism, means for giving a corresponding movement to said looping mechanism, an oscillating presser table, means for imparting a simultaneous rearward movement to said table, a clamping member operable 70 relatively with said looping mechanism to hold the fabric upon said table against said work holder, a tacking mechanism adapted to repeatedly press the fabric to fasten it in plaited condition after it has been acted 75 upon by said looping mechanism.

19. A machine of the kind described, comprising a guide table, a work holder comprising a plaiting wheel having a series of horizontal pins extending outwardly near 80 the periphery of the external vertical face, means for moving said wheel intermittently, a presser table located adjacent thereto and beneath said pins, means for imparting a simultaneous rearward movement thereto, a looping mechanism comprising a plunger located above said wheel and above the forward end of said table and adapted on its downward stroke to loop the fabric about 85 said pins, means for moving said plunger when said wheel is stationary, a clamping member operable relatively therewith to hold the fabric on said table about said pins as said plunger is raised, means for moving said clamping member in a manner corresponding to the movement of said plunger, a tacking mechanism mounted above said wheel and said table and adapted to press the fabric to fasten it in a plaited condition 90 after the operation of said plunger, and 100 means for moving said tacking mechanism.

20. A machine of the kind described comprising a reciprocating presser table, a reciprocating tacker adapted to press the fabric against said table, a looper adapted to engage the fabric and draw it from the source of supply to form a loop, means for holding the fabric during the withdrawal of the looper, and means for carrying the loop under the tacker while said tacker is 105 in a position out of engagement with said fabric.

ARTHUR J. WILLS.
